(57) **CLAIM**

We claim the ornamental design for a medical device holder, as shown and described.

DESCRIPTION

FIG. 1 is perspective view of a medical device holder, showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an enlarged view of FIG. 1; and,

FIG. 9 is a reference view thereof showing a configuration of use.

The broken lines in the drawings show portions of the medical device holder or show environmental structure which form no part of the claimed design.
